UNITED STATES PATENT OFFICE.

WALTER FREMONT CHURCH, OF GREELEY, COLORADO; MARY MUNCY CHURCH EXECUTRIX OF SAID WALTER FREMONT CHURCH, DECEASED.

WINDOW SHADE.

Application filed September 6, 1922. Serial No. 586,477.

To all whom it may concern:

Be it known that I, WALTER FREMONT CHURCH, a citizen of the United States, and a resident of Greeley, in the county of Weld and State of Colorado, have invented a new and Improved Window Shade, of which the following is a full, clear, and exact description.

My invention relates to window shades for curtains of the type including two shades or shade portions, both adapted to be drawn from the same roller in opposite directions when such roller is located at a point intermediate the top and bottom of the window, so that on imparting a turning movement to the roller one curtain or curtain portion is drawn up to shade the upper part of the window and the other is simultaneously drawn down to shade the lower part of the window.

The particular object of the present invention is to provide new and improved and very much simplified controlling means for thus manipulating a window shade of the above general character.

I am, of course, aware that very many different types of such controlling means have been proposed.

The object of my invention, however, is to provide a novel controlling means having the particular advantages that, with a single roller, preferably a spring roller of the well known Hartshorne type, and also with the lower curtain or curtain portion provided with the single short centrally pendant cord commonly pulled to raise or lower a single shade or curtain hung on such a roller located at the top of the window, the new shade of my invention may have its two curtain portions adjusted as desired merely by pulling said pendant cord in the usual manner and, therefore, merely by using one hand at all times; while at the same time providing a really positive elevating means for the upper curtain by virtue of having elevating elements to act on opposite ends of the upper edge of the latter curtain and operated by flexible connections to the opposite ends of the roller, in such manner that the entire operating means for the curtain may be disposed attractively and in confined vertical lines overlying the side sills of the window, so that the entire device is symmetrical and balanced, not only mechanically but aestheti-

cally, and thereby incidentally obviating cord complexities, and minimizing cord lengths, the number and variety of cord guiding fixtures required, the work of installing the entire curtain equipment and the manufacturing expense of the latter.

Other objects will be in part obvious and in part pointed out hereinafter.

All the objects will be more clearly understood from the following description when taken in connection with the accompanying drawing showing one example of a possible manner in which my invention may be embodied; it being, of course, understood that the scope of protection contemplated is indicated by the appended claims.

In this drawing, merely illustrative of the general character of the invention as above noted, and in which like characters refer to like parts throughout the several views,

Figure 1 is a front elevation of a curtain equipment according to my invention;

Figure 2 is a side elevation thereof; and

Figure 3 is an enlarged fragmentary view, being a section taken on the line 3—3 of Figure 1.

From this drawing it will be seen that my improved window shade equipment comprises merely a pair of upper fixtures 4, a pair of flexible elements 5 and a pair of drums 6 fixed on the outer ends of the curtain roller in combination with a curtain of the type above explained, including two curtain portions 7 and 8 and journaling means for the roller carrying both said curtain portions.

Preferably, these drums 6 are formed integral with the terminal ferrules on the roller; and so, at each end of the roller beyond the drums 6, are the usual reduced portions constituting pin and blade for journaling a Hartshorne roller in the well known manner in the stock Hartshorne brackets 9, but, of course, with these brackets as shown located intermediate the top and bottom of the window.

In addition to the foregoing simple, inexpensive, easily installed and not unattractive set of very few parts, the usual pendant operating cord here attached to lower curtain 8 is also desirably incorporated.

Further, I prefer to seam the upper free end of upper curtain 7 in the usual manner, as indicated at 11, not only to prolong the life of the curtain, but also to permit a

light wooden slat 12 to be accommodated inside the seam and to have projecting opposite ends to constitute a convenient and inexpensive and readily renewable anchorage for the depending lengths of flexible elements 5.

Each fixture 4, it will be noted, is preferably comprised of a unitary bracket of simple form and adapted to be inexpensively made from sheet metal, the bracket having journaled therein, one above the other, a pair of short rollers or drums 13 and 14, over the upper one of which the flexible element 5 is looped and behind the lower one of which said element is guided to confine the portion of the flexible element running down to slat 12 to a predetermined line of descent and to increase the frictional hold of the fixture on its flexible element. It is, of course, immaterial whether or not the two curtain elements 7 and 8 are separate curtain members secured along their joined ends to the roller or are folded over portions of a single curtain member secured along the line of fold to the roller, as shown in Figure 3. It will be understood, therefore, that the term "curtain" or "curtain portion" as employed herein refers to either type of curtain element, that is, a curtain portion or a curtain member.

The operation of the above device should be obvious. To simultaneously extend the two curtains or to simultaneously retract the same as desired, the cord 10 is merely pulled against the tension of the well known spring means within the Harts-horne roller; the action being precisely like the familiar one encountered when using such a roller carrying the ordinary single curtain at the top of a window. And it will also have been seen that I have provided an exceedingly simple, inexpensive, reliably operating and comparatively inconspicuous construction and one otherwise well adapted to attain all the various ends and objects herein above stated.

It will, of course, be understood, nevertheless, that the invention may be variously carried out without following the precise details of construction and arrangements of parts as particularly described in connection with the illustrative disclosure of the drawing so long as the spirit of the invention is adhered to as pointed out in the following claims:

I claim:

1. In a window shade including a single roller having wound thereon a plurality of curtain elements adapted to be simultaneously unwound from the roller one toward the top of the window and the other toward the bottom of the window, the combination of drums fast on the respective ends of the roller, a plurality of drums on fixed axes directly above the respective

drums on the roller and located at the top of the window, and a single flexible element secured at one end to each of the drums on the roller and running thence upwardly over the overlying drum at the top of the window and running thence downwardly and having its other end secured to the top of the upper curtain element.

2. In a window shade including a single roller having wound thereon a plurality of curtain elements adapted to be simultaneously unwound from the roller one toward the top of the window and the other toward the bottom of the window, the combination of drums fast on the respective ends of the roller, a plurality of drums on fixed axes directly above the respective drums on the roller and located at the top of the window, and a single flexible element secured at one end to each of the drums on the roller and running thence upwardly over the overlying drum at the top of the window and running thence downwardly and having its other end secured to the top of the upper curtain element, there being associated with each drum at the top of the window a guiding and confining means for the flexible element on that side of the window and engaging the part of said element extending between the drum last mentioned and the upper curtain.

3. In a window shade including a single roller having wound thereon a plurality of curtain elements adapted to be simultaneously unwound from the roller one toward the top of the window and the other toward the bottom of the window, the combination of drums fast on the respective ends of the roller, a plurality of drums on fixed axes directly above the respective drums on the roller and located at the top of the window, and a single flexible element secured at one end to each of the drums on the roller and running thence upwardly over the overlying drum at the top of the window and running thence downwardly and having its other end secured to the top of the upper curtain, there being an auxiliary drum located below each drum at the top of the window for frictionally engaging and additionally guiding the flexible element on that side of the window.

4. In a window shade including a single roller having wound thereon a plurality of curtain elements adapted to be simultaneously unwound from the roller one toward the top of the window and the other toward the bottom of the window, the combination of drums fast on the respective ends of the roller, a plurality of drums on fixed axes directly above the respective drums on the roller and located at the top of the window, and a single flexible element secured at one end to each of the drums on the roller and running thence upwardly over

the overlying drum at the top of the window and running thence downwardly and having its other end secured to the top of the upper curtain, there being an auxiliary drum located below each drum at the top of the window for frictionally engaging and additionally guiding the flexible element on that side of the window, and there being further provided a unitary bracket having 10 journaled thereon one of the drums at the top of the window and the auxiliary drum for the drum last mentioned.

5. In a window shade including a single roller having wound thereon a plurality of 15 curtain elements adapted to be simultaneously unwound from the roller one toward the top of the window and the other toward the bottom of the window, the com-

bination of drums fast on the respective ends of the roller, a plurality of drums on 20 fixed axes directly above the respective drums on the roller and located at the top of the window, and a single flexible element secured at one end to each of the drums on the roller and running thence upwardly 25 over the overlying drum at the top of the window and running thence downwardly and having its other end secured to the top of the upper curtain element, the upper curtain element having a transverse slat carried thereby at its upper end, the ends of the slat protruding beyond the side edges of the upper curtain, one end of each flexible element being secured to one of the protruding ends of the slat.

WALTER FREMONT CHURCH.
